DISPENSING SYSTEM

Arthur N. Kerr, Los Angeles, Calif., assignor to
Phillips Petroleum Company, a corporation of
Delaware

Application July 20, 1940, Serial No. 346,632

4 Claims. (Cl. 62—1)

This invention relates to the storage and utilization of fuel gases.

More particularly, it relates to a dispensing system for fluids stored under pressure and is especially adapted for use with liquefied fuel gases.

Propane and mixtures of propane and butane are being marketed at the present time for home or industrial uses in communities where natural gas is not available. The gases in liquefied state are packaged for home use in small individual containers to facilitate transportation. To use gas from the containers it is necessary only to connect the containers to suitable pressure reducers which are in communication with the service line leading to the customer's appliances.

The gases being used at present in this manner are those having boiling points sufficiently low as to be vaporized at outside temperatures even on a cold day. The commercial "butanes," a by-product of the petroleum industry are available in many communities at low cost. Because of their boiling range, 10-34° F., they have not been used in the conventional air warmed home dispensing equipment in regions where the atmospheric temperatures are subject to drop below the boiling point temperature of the butanes. If the containers are exposed to temperatures below the atmospheric boiling point of the liquid the vaporization stops, causing a cessation of the supply of gas to the user's appliances. A number of hazards might result from the failure of the gas supply during the cold period, which is usually at night, and the continuance of the gas supply when the containers are again warmed up. The present invention provides dispensing equipment which is especially designed for use in dispensing liquefied hydrocarbons having a boiling point of less than 50° F. at atmospheric pressure. This is accomplished by providing dispensing equipment in which the liquefied gas containers are maintained at a temperature above the atmospheric boiling point of the liquefied gas. Such equipment is especially adapted to dispensing the commercial butanes for home consumption in moderate climates, such as the southern part of the United States.

An object of this invention is to provide improved liquefied gas dispensing equipment.

A further object of this invention is to provide a means of maintaining liquefied gas containers at temperatures above the atmospheric boiling point of the liquefied gas contained therein.

The accompanying drawing is an elevation view

partly in section of a specific embodiment of apparatus suitable for carrying out my invention.

Referring to the drawing, the numeral 1 designates a protective housing adapted to be mounted on a wall or other supporting surface 2. The housing may be provided with a layer of insulation 3 on the sides exposed to atmospheric temperature variations and a leak proof inner lining 4. A hinged cover 5, forming the top of the protective housing provides access to the interior. The liquefied gas container 6 from which gas is to be dispensed is positioned in the housing by vertical guide members 7. The gas formed by vaporization in the container is withdrawn through a suitable pressure regulator 8 and flexible conduit 9 to the customer's supply line 10. Although only one container is visible in the accompanying drawing, it will be apparent to those skilled in the art that a plurality of containers may be contained in the protective housing 1 and that they may be connected to the customer's service line in a similar manner. Since the gas in the container is usually in liquefied form it is obvious that if withdrawal is made below the surface of the liquid, the liquefied gas will be vaporized upon reduction in pressure. This would be the case if the container 6 were in the position shown by Figure 1 inverted.

The housing contains water 11 which is supplied thereto through the inlet pipe 12 and a thermostat-controlled valve 13 from a water supply pipe 14. The water in heat exchange relation with the liquefied gas container is maintained at a predetermined level by the overflow pipe 15. A coil 16 is disposed in the lower portion of the housing in heat exchange relation with the water contained therein and is connected to the water supply pipe 14. Water from the supply pipe may be passed through the coil 16 from which it is passed through the pipe 17 and control valve 18 to the point of use. A thermostat 19 in contact with the water in the housing controls admission of water to the housing through the valve 13 and the inlet pipe 12. The thermostat is set automatically to admit water to the housing from the supply pipe when the temperature of the water in the housing reaches a predetermined minimum.

The buoyancy of the container when immersed in water offers a means of determining the degree of depletion of the container. As gas is withdrawn from the container through the flexible conduit 9, the weight of the contents of the container decreases and the container tends to rise. The vertical guide members 7 maintains the container in an upright position and allow it to rise

freely. A graduated gauge rod 20 is attached to the top of the container and extends upwardly through a slot 21 in the cover 5 of the housing. As the container rises, an increasing amount of the gauge rod is exposed to view above the top of the housing, thus giving a visible indication of the quantity of liquid remaining in the container.

It is apparent that the dispensing system of this invention is adaptable for use with a variety of volatile liquids and liquefied gases. With any liquefied gas, the minimum to which the temperature of the water 11 is allowed to drop, as controlled by the thermostat 19, is some temperature above the atmospheric boiling point of the liquefied gas, and above the freezing point of the water. It will be understood that in warm climates where atmospheric temperatures are relatively high, very little, if any, water will be required to maintain the temperature of the water 11 above the desired minimum, which may be 40° F. to 50° F. for commercial butanes. In regions where the atmospheric temperature drops below the desired minimum temperature for only short periods of time, the water in the housing may have sufficient heat capacity to supply the required heat to the container during the atmospheric cold period without dropping below the minimum temperature.

Water supplied to the housing from the supply pipe 14 may be at any temperature above the desired minimum temperature. Water from the ordinary household supply pipe may be available at such temperature. In regions where the climatic conditions are such that low atmospheric temperatures prevail for long periods of time, it may be desirable to supply heated water from a suitable source to the system through the supply pipe 14.

The high rate of heat transfer from the water to the container makes it desirable to supply water for warming the container through the inlet 12. It is to be noted, however, that any water withdrawn through the valve 18 will pass through the coil 16 which is in heat exchange relationship with the water 11 in the housing 1. In passing through the coil 16, the water in the coil gives up heat to the water 11 surrounding the coil. Thus it is evident that the coil 16 may be used as a means for cooling the water withdrawn from the supply pipe 14 through the coil 16, pipe 17 and valve 18. In warm climates this affords a source of supply of cooled drinking water. It will be evident that the coil 16 also serves as a secondary heating means for heating the water 11.

I claim:

1. In a liquefied gas dispensing system, a protective housing adapted to contain water, a liquefied gas container in the protective housing, means for withdrawing gas from the liquefied gas container, means for supplying water to the protective housing in heat exchange relation with the liquefied gas container, a secondary heating means in heat exchange relation with the water in the protective housing, means for supplying water to said secondary heating means, and means for controlling the supply of water to the protective housing in accordance with changes in temperature of the water in the protective housing.
- 5 2. In a liquefied petroleum gas dispensing system, a protective housing, vertical guides therein, a liquefied gas container between said guides, a gas service line connected to the liquefied gas container, a fluid medium surrounding the liquefied gas container in heat exchange relationship, means for maintaining the temperature of the fluid medium above a minimum, and a gauging device attached to the container, said gauging device responsive to change in weight of the container contents.
- 10 3. In a liquefied gas dispensing system, a protective housing adapted to contain water, a liquefied gas container in the protective housing, means for withdrawing gas from the liquefied gas container, means for supplying water to the protective housing in heat exchange relation with the liquefied gas container, a secondary heating means in heat exchange relation with the water in the protective housing, means for supplying a fluid heating medium to said secondary heating means, and means for controlling the supply of water to the protective housing in accordance with changes in temperature of the water in the protective housing.
- 15 4. In a liquefied petroleum gas dispensing system, a protective housing, vertical guides therein, a liquefied gas container between said guides, a gas service line connected to the liquefied gas container, a fluid medium surrounding the liquefied gas container in heat exchange relation, a thermostat for maintaining the temperature of the fluid medium above a minimum, and a gauging device attached to the container, said gauging device responsive to change in weight of the container contents.

ARTHUR N. KERR.
